UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

SOLE ROUNDING AND CHANNELING MACHINE.

1,117,303.

Specification of Letters Patent. Patented Nov. 17, 1914.

Application filed June 11, 1908. Serial No. 437,888.

To all whom it may concern:

Be it known that I, HARRIE A. BALLARD, of Boston, in the county of Suffolk and State of Massachusetts, have invented certain new and useful Improvements in Sole Rounding and Channeling Machines, of which the following is a specification.

This invention relates to machines for rounding and channeling the soles of shoes while they are upon the last, and is an improvement upon the machine shown in my co-pending application filed Jan. 11, 1905, Serial No. 240,532, (now U. S. Patent No. 1099334, issued June 9, 1914.)

One of the essential features of the present invention is the means for intermittently clamping and feeding the work step by step.

Another feature is the construction and arrangement of a pair of work guides, either of which is adapted to operate to the exclusion of the other whenever the nature of the work makes it desirable.

Still another feature is the construction of the cutting and feeding means whereby it may be moved with relation to the work guides without stopping or otherwise affecting its operation. The capacity for so moving the cutting means is that by reason of which the width of the sole extension may be varied while the machine is in operation.

By means of a machine constructed in accordance with this invention it is possible to cut entirely around the edge of the sole, and while the machine is in operation to vary the space between the edge of the sole and the channel or to entirely remove the channeling tool, and to place in operative position a movable work guide adapted to guide the work by means of the lasted portion of the shoe.

Other features are hereinafter described and are illustrated upon the accompanying drawings of which—

Figure 1 is a side elevation of the operative portion of a sole rounding and channeling machine. Fig. 2 is a section and plan on line 2—2 of Fig. 1. Fig. 3 is a longitudinal vertical section of the said portion. Figs. 4, 5, 6 and 7 are sectional views on lines 4—4, 5—5, 6—6, and 7—7 respectively of Fig. 3. Fig. 8 is a sectional view of greater scale of the channel knife slide. Fig. 9 is a sectional view of means for mov-

ing the movable work guide. Fig. 10 is a vertical sectional view of greater scale of the several work-engaging elements. Fig. 11 is an end elevation of the cutting, feeding and channeling devices. Fig. 12 is a section on line 12—12 of Fig. 10. Fig. 13 is a vertical section similar to a portion of Fig. 2 but illustrating a difference of position. Fig. 14 on a still greater scale shows a plan of the rounding knife and its path of movement. Fig. 15 is a vertical section of an adjustable link connection shown in Fig. 13. Fig. 16 is a section on line 16—16 of Fig. 14. Fig. 17 is a side elevation of a treadle and connection for moving the channeling knife support and work guide.

The same reference characters indicate the same parts wherever they occur. The several instrumentalities hereinafter described are installed in a head or frame 10 which may be mounted, as shown by Fig. 1, upon a base or standard 11 of which a fragment appears. It may be presumed that the base is equipped with two or more treadles or other actuators for controlling such instrumentalities as are manually operable.

The head 10 is an open structure somewhat resembling a shell and it contains a movable casing or frame 12 in which is installed the edge cutting and work feeding means. By way of mounting the casing 12, it is provided with bushings 13 which constitute trunnions and also bearings for a power shaft 14. For convenience of manufacture the casing is made of two sections bolted together, and the bushings are clamped between the sections and project on either side into bearings formed in the head 10. In this way provision is made for rotation of the shaft, and for oscillation of the casing 12 about the same axis, for a purpose hereinafter explained.

The farther end of the casing 12 normally rests upon a seat 15 from which it may be raised as shown by Fig. 13, and is furthermore confined by parallel guides 16 formed on the head. See also Figs. 2 and 6. This end of the casing is provided with bearings for the trunnions 17 of an oscillatory hanger 18 on which is formed a sleeve 19 constituting a bearing for a reciprocatory carrier 20. The bearing for the carrier extends transversely with relation to the axis

of the trunnions 17, so that by means of the carrier the hanger 18 may be oscillated upon its trunnions.

One end of the carrier 20 extends into the 5 casing 12 and is provided with an eccentric strap 21 surrounding an eccentric 22 mounted upon a stud shaft 23. The shaft is mounted in bearings formed in the casing 12, and its axis is parallel to that of the 10 trunnions 17. Rotation is imparted to this shaft from the shaft 14 by the helical gears 24 and 25. Rotation of the eccentric shaft 23 imparts circular motion to one end of the carrier 20, thereby causing the latter to 15 move back and forth in the sleeve 19 and by reason of its ever changing angle, to oscillate the hanger 18 upon its trunnions 17.

The outer end of the carrier 20 carries a work clamping and feeding member 26 and 20 a cutting knife 30 whose form is shown best by Figs. 10 and 14. The said clamping member and knife are adapted to coöperate with a cutting block 31 which is affixed by a bolt to the overhanging portion of the 25 hanger 18. The clamping member 26 and the cutting block 31 are so arranged that the edge of a sole *a* may be clamped by and between them in the path of the cutting knife 30.

30 The clamping member 26 as shown by Fig. 11, is a head formed on the outer end of a plunger 27 which extends into a chamber formed in the carrier 20. Bearings for the plunger are indicated at 28 and 29, the 35 former being a bushing affixed in the carrier and of non circular cross section for the purpose of preventing axial rotation of the plunger which is of similar cross section at that point. Between the bearings 28 and 29 40 are two helical springs 32 and 33 surrounding the plunger 27, and between the springs is a collar 34 affixed upon the plunger. The plunger, when unobstructed, moves axially with the carrier 20, but is adapted to yield 45 under tension of the spring 32 when clamping the work against the cutting block. The spring 33 is merely a cushion for the purpose of arresting the recoil of the collar 34 without causing objectionable noise.

50 The rear end of the knife 30 is of dovetail cross section and is adjustably affixed to the carrier by means of a split collar 35 surrounding the carrier and having a dovetail groove for the knife. A bolt 36 serves the 55 two-fold purpose of locking the collar upon the carrier and of clamping the knife shank in the collar. By reason of the circular motion given one end of the carrier 20, the cutting end 37 of the knife 30 receives a movement similar to that indicated by the dotted ellipse in Fig. 14. A slot 40 formed in the work-engaging face of the cutting block permits the edge 37 of the knife to advance 60 beyond said face and cut entirely through 65 the work. By reason of the oscillatory

movement imparted by the carrier 20 to the hanger 18, the cutting block on the hanger receives a lateral reciprocatory movement corresponding to that of the clamping head 26 and cutting knife 30, as indicated by dotted lines in Fig. 14. The side edges 38 and 39 of the knife are sharpened and converge slightly in order to render the cutting action as smooth as possible. 70

When the work is in operative position as shown by Fig. 10, it engages a fixed guide 41 hereinafter termed the forepart guide. This guide, though adjustable, is rigidly affixed as by bolts 140 to the head 10, and is adapted to engage the upper *b* of the shoe at or near the inseam joining the upper and innersole. In practice this guide is used when rounding the forepart of the sole, and may be used also in rounding the heel seat, but for the latter purpose another guide, hereinafter 80 termed the heelseat guide, may be used if desired. When the shoe is held upwardly against the guide, it is advanced step by step in one direction by the clamping and feeding means and rounded by the knife 30 while 90 being fed. Upon each retrograde movement of the carrier 20, the knife 30 is entirely withdrawn from the work by the clamping head 26, and although its clamping tension is somewhat relieved, the clamping 95 head is never withdrawn from engagement with the work. A slight pressure of the work against the guide 41 is generally sufficient to prevail over the retrograde tendency of the work when the cutting block and 100 clamping head move back laterally for a new hold upon the sole.

The cutting and guiding devices as shown by Figs. 1, 3 and 10, are so related as to cut the sole relatively close to the upper, but 105 may be caused to cut farther from the upper so as to leave what is sometimes termed a "wide extension" at any desired part of the sole. This is accomplished by moving the cutting mechanism to another position as 110 shown by Fig. 13 in which the forward end of the casing is raised above its seat 15. The means for raising the casing includes a link 42, a lever 43 and a manually operative rod 44 which may be connected to a treadle not 115 shown. The lever is fulcrumed in the head upon trunnions 45 (see Fig. 7) and has several branch arms of which one is pivotally connected to the rod 44 and one to the link 42. The link contains an adjustable rod 46 and an adjusting screw 47 therefor. The upper end of the rod is adapted to engage and raise a bolt or projection 48 carried by the casing 12 (see also Fig. 2). When the rod 44 is depressed, it tilts the lever 43 and raises the link 42 which may be so adjusted as to raise the casing 12 an equal distance, or any less distance. It may, on the other hand, be so adjusted as to be ineffective for raising the casing, this being determined by 120 125 130

the amount of space between the upper end of the rod 46 and the bolt 48. When, however, the casing is raised, it turns upon its trunnions 13, thereby carrying the entire work cutting, clamping and feeding mechanism, about the axis of the gear 25 without disturbing the driving relation with the latter. As a result of moving the cutting point relatively to a stationary work guide that 10 surface of the work by which the cutting is gaged bears a fixed predetermined relation to the operative under all conditions. For limiting the upward movement of the casing 12, the head 10 is provided with an adjustable stop screw 49.

The heelseat guide hereinbefore mentioned, is indicated at 50 and is vertically movable in a groove in the front of the head 10 in which it is confined by the fixed guide 20 41. The guide 41 extends across the path of the movable guide but is provided with an aperture 51 through which the latter guide moves. As illustrated by Fig. 10, the heelseat guide is elevated to inoperative position 25 but its work-engaging position is shown by dotted lines. The means for moving the said guide includes rack teeth 52 formed thereon, and an intermeshing pinion 53 affixed upon one end of a stem 54. The stem 30 is rotatably mounted in the head 10 (see Figs. 3 and 4) and carries also grooved pulley 55 on its outer end. By rotating the pulley the guide may be moved to or from work-engaging position and according to the 35 present arrangement, it is normally elevated by a spring 56 to which it is connected by one end of a chain 57. One link of the chain is made fast to the pulley by a screw 58 (see Fig. 9) and the other end of the chain 40 may be employed to manually depress the guide against the tension of the spring 56. For this purpose, the head 10 is provided with an idle pulley 59 over which the chain may run to be connected to an actuator such 45 as a treadle 150. It may be observed that the relation of the two guides 41 and 50 with the work is such that neither the work, nor its relation with the guide 41 is disturbed by the guide 50 until the latter is in position 50 to guide the work, and so no objectionable disturbance is effected if the movable gage is depressed during feeding of the work.

A channeling knife 60 is provided for 55 operating in conjunction with the rounding operation, to cut a channel in the tread surface of the sole at any desired distance from the edge thereof. The channeling knife (see Figs. 10 and 11) is clamped by means of screws 61 in the split head 62 of an adjustable post 63. The post is mounted in a block 64 and its lower end is screw-threaded and provided with an adjusting nut 65 confined in the block 64. By means of the nut 60 the post may be moved toward or from the 65 rounding knife, but is otherwise maintained

in rigid position by reason of having a non-circular portion 66 conforming with a similar bearing in the block. (See Fig. 8.) A screw 67 limits the range of adjustment of the post.

The block 64 is mounted in dovetail guides in a carriage 68 in which it is movable toward and from the rounding knife. The means for raising the rounding knife is employed to also raise the block and for this 70 purpose the lever 43 is provided with an arm 69 having a radial slot 70. The slot is occupied by an adjusting screw 71 which carries a square block 72 adapted to slide in a slot 73 formed in an ear 74 of the block 64. An adjustable connection is thus established by which the block 64 may be raised and lowered in the carriage 68 whenever the rod 44 is actuated. The effect upon the work, when the channeling knife is raised 80 relatively to the rounding knife, is to decrease the space between the edge of the sole and the channel. It will be remembered, however, that the rounding knife may also be raised by the rod 44 but that, by certain 85 adjustment of the link 42, a part or all of the movement of the latter may be rendered ineffective. If the link be so adjusted as to impart the full movement to the casing 90 12, actuation of the rod 44 causes concurrent 95 movement of both the channeling and rounding knives, thus increasing the extension of the sole but keeping the same relative distance between the edge of the sole and the channel. But, on the other hand, if the link 100 42 be so adjusted as to not move the casing 12 during the first part of its movement, actuation of the treadle rod first causes the channeling knife to approach the edge of the sole, and then causes both knives to move 105 together in the same direction.

The channeling knife, in addition to being movable toward and from the rounding knife, is movable transversely or away from the work and may be withdrawn from work-engaging position. In practice the channeling knife is withdrawn while rounding the heelseat, but is normally in work-engaging position as illustrated. The carriage 68 is mounted in the head 10 in dovetail guides 110 75 (see Figs. 6 and 13) in which it is movable in and out. A helical spring 76 coiled about a rod 77 affixed to the rear end of the carriage is compressed between the carriage and a fixture 78 in which the rod has a sliding fit. The spring normally tends to press the carriage forward to operative position, but the latter may be manually retracted when desired, and for the purpose, a hand lever 80 is pivoted at 81 to the right side of 115 the head 10. Connection between the lever 80 and the carriage is by means of a rod 82 which projects laterally from the carriage through a slot in the head and a radial slot 83 in the lever, see Figs. 1 and 6. The lever 120 125 130

80 may be actuated by hand to retract the carriage, and by means of a chain 84 it may be connected to the treadle 150 and thereby actuated if desired.

5 It will be remembered that in rounding the heelseat I prefer to employ the heelseat guide 50 and to retract the channeling knife to inoperative position, and that at no other time is it desirable to change the normal 10 positions of these elements. In practice I prefer to connect both of the chains 57 and 84 to the same treadle in such a way that actuation of the treadle may move the guide 50 and channeling knife simultaneously, one 15 into work-engaging position and the other to inoperative position.

Having thus explained the nature of my said invention and described a way of constructing and using the same, although 20 without attempting to set forth all of the forms in which it may be made or all of the modes of its use, what I claim is:—

1. A machine of the character described, comprising work-clamping and feeding means, and a rounding knife carried thereby and operatively moved by the clamping and feeding movement of said means.

2. A machine of the character described, comprising a movable rounding knife, a 30 carrier therefor, a movable cutting block so connected to the carrier as to be reciprocated thereby, and work-clamping means on said carrier adapted to coöperate with the cutting block in clamping and feeding the 35 work.

3. A machine of the character described, comprising a cutting block movable about a fixed axis, a rounding knife movable toward and from the cutting block transversely of said axis and also movable about the axis, a carrier for the knife, and means 40 on the carrier adapted to coöperate with the cutting block in clamping and feeding the work.

4. A machine of the character described, comprising the three following elements 45 movable in unison about a common axis, viz., a rounding knife, a cutting block therefor, and means adapted to coöperate with the cutting block in clamping the work, said knife being also movable toward and from the cutting block.

5. A machine of the character described, comprising an oscillatory member, a carrier 55 having a bearing therein, in which it is adapted to move transversely of the axis, an actuator for imparting to a point of the carrier circular motion about an axis parallel to that of the member, a cutting 60 block affixed to the member, a rounding knife upon the carrier for coöperation with the cutting block, and means on the carrier adapted to coöperate with the cutting block in clamping the work.

6. A machine of the character described,

comprising a cutting block, a carrier movable toward and from the cutting block, and a rounding knife and yielding work clamp carried by the carrier, the knife being adapted to cut and the clamp to clamp the 70 work against the cutting block.

7. A machine of the character described, comprising a cutting block movable about an axis, a rounding knife likewise movable about said axis and also movable radially 75 of said axis toward and from the cutting block, and a work-clamping device movable about said axis and radially of the axis toward and from the cutting block.

8. A machine of the character described, comprising a movable cutting block, a rounding knife and work-clamping member movable toward and from the cutting block, and movable together with the cutting block transversely of said first movement, said cutting block, rounding knife and clamping member being so organized as to be operable by means of one and the same actuator.

9. A machine of the character described, comprising means for moving the work step 90 by step in one direction, and a knife carried and actuated by said means so as to penetrate and slice the edge of the work during the feeding thereof.

10. A machine of the character described, comprising an edge-cutting knife movable for varying the width of stock between its cut and the body of the shoe, a channeling knife movable for varying the distance between the trimmed edge of the sole and the 100 channel, manually operative means for moving one of said knives as specified, and means for transmitting such manually effected movement of the last-mentioned knife to the other knife for the purpose 105 specified.

11. A machine of the character described, comprising work-guiding means, a channeling knife, a driving element, and the following instrumentalities movable as a whole 110 relatively to the guiding means, channeling knife and driving element, viz.,—edge-cutting and work-feeding means, and actuating means therefor, said actuating means being in undisturbed driving relation at all times 115 with said driving element.

12. A machine of the character described, comprising an edge-cutting knife movable for varying the width of stock between its cut and the body of the shoe, a channeling 120 knife movable for varying the distance between the trimmed edge of the sole and the channel, means for moving the channeling knife for the purpose specified, and means for transmitting such movement to the edge-cutting knife for the purpose specified.

13. A machine of the character described, comprising an edge-cutting knife movable for varying the width of stock between its cut and the body of the shoe, a channeling 130

knife movable for varying the distance between the trimmed edge of the sole and the channel, means for moving the channeling knife for the purpose specified, and means 5 for transmitting such movement to the edge-cutting knife for the purpose specified, said transmitting means having provision for permitting movement of the channeling knife as specified without moving the edge-cutting knife, and having means for varying the extent to which said channeling knife may be moved without causing movement of the edge-cutting knife.

14. A machine of the character described, 15 comprising a rounding knife, means for operating the same, a movable channeling knife, and means for communicating movement from one of said knives to the other to adjust one by the other.

20 15. A machine of the character described, comprising a work guide, a channeling knife movable relatively to said work guide, a rounding knife movable transversely of its plane of cutting movement, and means for 25 communicating movement from said channeling knife to said rounding knife to adjust the latter from one plane of cutting movement to another.

16. A machine of the character described, 30 comprising a work gage, two knives for operating upon the sole of a shoe, one for channeling the sole and the other for trimming the sole, means for adjusting one of said knives, and connections between said 35 means and the other knife for adjusting the latter whereby both knives may be adjusted simultaneously relatively to said gage to vary the width of the margin of the sole.

17. A machine of the character described, 40 comprising an edge-cutting knife, a fixed guide for the work, a channeling knife movable to and from operative position, a movable work-guide for displacing the work from said fixed work-guide, manually operative means for moving said channeling knife away from operative position and for moving said movable work-guide to displace the work as specified, and means for moving the channeling knife from operative 45 position without moving said movable work-guide.

50 18. A machine of the character described

comprising a frame, a driving shaft, a closed casing movably mounted on the shaft, work-feeding and edge-cutting means supported by said casing, an actuator inclosed within the casing for operating the feeding and cutting means, and means driven by the shaft within the casing for driving said actuator.

19. A machine of the character described, comprising a rounding knife, a channeling knife, and a single means for communicating movement to both of said knives for adjusting them simultaneously without disengaging either from the work.

20. A machine of the character described, comprising a slide, guides therefor, guides on said slide transverse to those in which the slide is arranged, a holder mounted to 70 slide in the guides on said slide, a channeling knife on said holder, a rounding knife movable transversely of its plane of cutting movement, means for moving said channeling knife holder relatively to said 75 slide, and connections between the channel knife holder and the rounding knife for transmitting movement from said holder to shift said rounding knife from one plane of cutting movement to another.

80 21. A machine of the character described, comprising a work-guide, a rounding knife adapted to be shifted transversely of its plane of cutting movement, a channeling knife adapted to be shifted, and a single 85 manually operative means for shifting said knives at will relatively to said work guide and relatively to each other.

22. A machine of the character described comprising a rounding knife, a channeling 90 knife, and a single means for communicating movement to both of said knives for adjusting them simultaneously to vary the marginal portion of the sole, said means having provisions for varying the adjusting movement of one independently of the other to vary the distance of the channel from the edge of the trimmed sole.

In testimony whereof I have affixed my signature, in presence of two witnesses.

HARRIE A. BALLARD.
